UNITED STATES PATENT OFFICE.

ALFRED H. HUMPHREY, OF NEW YORK, N. Y.

GAS-LAMP.

No. 880,797.

Specification of Letters Patent.

Patented March 3, 1908.

Application filed March 16, 1907. Serial No. 362,696.

To all whom it may concern:

Be it known that I, ALFRED H. HUMPHREY, a citizen of the United States, residing at the city of New York, county of New York, State of New York, have invented certain new and useful Improvements in Gas-Lamps, of which the following is a specification.

This invention relates to improvements in gas lamps.

The main objects of this invention are, first, to provide in a gas lamp of the inverted burner type, an improved burner. Second, to provide in a gas lamp of the inverted burner type, an improved construction and arrangement of the burner, whereby the parts may be readily assembled and adjusted. Third, to provide a gas lamp of the inverted burner type, in which the valves of the burner and burner tube are protected from the heat of the burner so that they do not become unduly heated, and the air inlet is protected from the products of combustion.

Further objects, and objects relating to details of construction, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is a detail side elevation of a structure embodying the features of my invention, only the chimney and burner, in connection with the gas supply pipe, being illustrated. Fig. 2 is a vertical longitudinal section through the burner, taken on a line corresponding to line 2—2 of Fig. 1. Fig. 3 is a transverse section, taken on a line corresponding to line 3—3 of Fig. 2. Fig. 4 is a transverse section, taken on a line corresponding to line 4—4 of Fig. 2. Fig. 5 is a longitudinal section of the burner tip with a modified form of deflector and screen.

In the drawing, the sectional views are taken looking in the direction of the little arrows at the ends of the section lines, and similar numerals of reference refer to similar parts throughout the several views.

Referring to the drawing, the chimney 1 is preferably provided at its lower end with an

outwardly and downwardly projecting flange 2, the flange being perforated to receive the burner, which is arranged in an inverted position therethrough, the general arrangement being that shown in my application for Letters Patent filed June 22, 1906, Serial Number 322,891. The chimney is preferably supported on the gas delivery pipe 12, it being attached thereto by any suitable means, as by the clip 13. On the gas delivery pipe 12 is a nipple 14, having an inverted gas delivery nozzle 15 thereon. The needle valve 16 controls the delivery of the gas from this nozzle.

The burner preferably consists of the burner tube 3 and the burner tip or delivery portion 5. The burner tube is arranged through the flange, as stated, and is preferably provided with an upwardly-tapered threaded portion 4, which is threaded into the flange of the chimney, thereby supporting the burner and effectively closing the opening in the flange through which it is inserted. The upper end of the burner tube is supported below the gas delivery nozzle, so that the gas is delivered centrally thereto. Threaded upon the nipple is a sleeve 10 having air inlet openings 11 therein, which are preferably of sufficient size to allow the manipulation of the gas delivery nozzle 15, or its removal or insertion without moving the sleeve. The sleeve is adapted to receive the upper end of the burner tube, guiding and supporting the same in proper relation to the gas delivery nozzle. The sleeve is also adapted to serve as a valve for controlling the air inlet.

The burner tube is provided with a flange-like enlargement 17 at its lower end and the burner tip or delivery portion 5 is provided with a corresponding enlargement at its upper end. These parts are preferably formed of suitable non-heat-conducting materials, so that the heat from the burner is not carried or conducted to the valves or to the burner tube. The burner tip 5 is detachably connected to the tube by a threaded coupling sleeve 6, which is arranged on the expanded or flanged lower end 17 of the burner tube, the same being prevented from turning thereon by the lugs 18. By thus forming and connecting the parts, the burner may be assembled in the lamp by threading the tube 3 through the chimney flange which brings it in proper position below the gas delivery nozzle, as described, the sleeve 10 properly guiding and supporting the upper

end thereof. The burner tip may be easily removed, as desired.

- I preferably provide the burner tip with a plurality of longitudinal projecting ribs 9, which assist in radiating the heat and also serve as effective grips for convenience in attaching or removing the burner. This arrangement prevents the undue heating of the burner tube above the chimney flange, as the chimney serves to draw the heat from the burner, and the burner tip and tube, being formed of non-heat-conducting material, do not by conductivity carry the heat to the parts above the flange, so that they are kept comparatively cool. By forming the burner tip and burner tube independently, they can be economically manufactured of the non-heat-conducting material and readily assembled.
- Another advantage is that, should the burner tip be destroyed, a new tip can be adjusted to the burner tube. The burner tube is preferably provided with a mixing chamber 21 for the air and gas, and with an expansion chamber 22, the upper end of the mixing tube serving as a mixing chamber and the lower end as the expansion chamber. The mixing chamber 21 is tapered or contracted downwardly, while the expansion chamber 30 is enlarged and expanded downwardly from the lower end of the mixing tube. The burner tip chamber 23 is contracted downwardly, as clearly appears from Fig. 2 of the drawing. The walls of the mixing chamber 35 are preferably formed with a parabolic curvature, as appears from an inspection of Fig. 2.

Between the gas delivery nozzle 15 and the mouth of the burner tip, the delivery nozzle and the mouth of the burner tip being preferably in alinement, as I have illustrated in the accompanying drawing, I arrange a deflector or baffle 7'. This deflector 7', which is preferably conical in form, is preferably supported on the screen 7 which is also preferably conical in form, as is illustrated in Fig. 2. The screen is preferably supported on an annular shoulder 20 provided therefor at the upper end of the burner tip, the deflector projecting into the lower end of the mixing chamber of the burner. The deflector when thus located receives the direct impact from the nozzle 15. This practically eliminates the blowing or roaring which is likely to be present, particularly where the gas is delivered under high pressure, and also prevents the destruction of the mantles as otherwise sometimes occurs where the gas is delivered under high pressure. The burning mixture is also more effectively delivered at the mouth of the burner tip for properly incandescenting the whole of the mantle. A further advantage of this arrangement is to prevent "back-lighting" or "back-firing," as it is called.

In the modified construction shown in Fig.

5 the deflector is shown mounted upon a flat screen. This form has the advantage of a slight economy of manufacture over that shown in Fig. 2.

The mixing chamber, expansion chamber, 70 and the contracted chamber of the burner tip divide the burner into three sections of substantially the same length, which I find produce very satisfactory results. The mantle, as 24, is supported about the burner tip 75 by a suitable mantle-holder 25, the details of the support not being here illustrated, as they form no part of this invention.

By supporting the burner tube by threading into the chimney flange, as illustrated 80 and described, I am enabled to effectively support the same, although it may be made of non-heat-conducting material, such as porcelain, magnesia, and the like, thus permitting the forming of large, strong threads 85 and avoiding the necessity of forming fine threads thereon, which would be necessary if the burner tube was to be supported from the nipple 14 or by threading into or upon the sleeve 10.

I have illustrated and described my improved gas lamp in detail in the form preferred by me on account of its structural simplicity and economy and the convenience in adjusting the parts when in use. I am, however, aware that it is capable of considerable variation in structural details without departing from my invention, and I desire to be understood as claiming the same specifically, as illustrated, as well as broadly. 90

Having thus described my invention, what I claim as new and desire to secure by Letters Patent is:

1. In a gas lamp, the combination with a gas delivery pipe, of a chimney connected thereto, said chimney having an outwardly-projecting flange at its lower end; a nipple on said gas delivery pipe; a downwardly-directed delivery nozzle threaded upon the lower end of said nipple; a valve for controlling said delivery nozzle; a sleeve adjustably-arranged on said nipple having openings in the sides thereof for the admission of air and for the manipulation of said nozzle, said openings being of sufficient size to admit of the insertion or removal of said nozzle therethrough; an inverted burner tube having a flange-like enlargement at its lower end, threaded through said chimney flange, arranged with its upper end projecting into said sleeve; an inverted burner tip having a threaded enlargement at its upper end corresponding in diameter to the lower end of the said burner tube; a coupling sleeve arranged on the enlarged lower end of said burner tube, into which said burner tip is threaded; and lugs on said burner tube adapted to engage said coupling whereby its rotation on said burner tube is prevented. 115
2. In a gas lamp, the combination with a 130

- gas delivery pipe, of a chimney connected thereto, said chimney having an outwardly-projecting flange at its lower end; a downwardly-directed delivery nozzle; a valve for controlling said delivery nozzle; a sleeve having openings in the sides thereof for the admission of air, arranged about said nozzle; an inverted burner tube having a flange-like enlargement at its lower end, threaded through 5 said chimney flange, arranged with its upper end projecting into said sleeve; an inverted burner tip having a threaded enlargement at its upper end corresponding in diameter to the lower end of the said burner tube; a coupling sleeve arranged on the enlarged lower end of said burner tube, into which said burner tip is threaded; and lugs on said burner tube adapted to engage said coupling whereby its rotation on said burner tube is 10 prevented.
3. In a gas lamp, the combination with a gas delivery pipe, of a chimney connected thereto, said chimney having an outwardly-projecting flange at its lower end; a nipple on 15 said gas delivery pipe; a downwardly-directed delivery nozzle threaded upon the lower end of said nipple; a valve for controlling said delivery nozzle; a sleeve adjustably-arranged on said nipple having openings in 20 the sides thereof for the admission of air and for the manipulation of said nozzle, said openings being of sufficient size to admit of the insertion or removal of said nozzle therethrough; an inverted burner tube having a 25 flange-like enlargement at its lower end, threaded through said chimney flange, arranged with its upper end projecting into said sleeve; an inverted burner tip having a 30 threaded enlargement at its upper end corresponding in diameter to the lower end of the said burner tube; and a coupling sleeve arranged on the enlarged 35 lower end of said burner tube, into which said burner tip is threaded.
4. In a gas lamp, the combination with a gas delivery pipe, of a chimney connected thereto, said chimney having an outwardly-projecting flange at its lower end; a downwardly-directed delivery nozzle; a valve for 40 controlling said delivery nozzle; a sleeve having openings in the sides thereof for the admission of air arranged about said nozzle; an inverted burner tube formed of non-heat-conducting material having a flange-like enlargement at its lower end, threaded through said chimney flange, arranged with its upper end projecting into said sleeve; an inverted burner tip formed of non-heat-conducting material having a threaded enlargement at its upper end corresponding in diameter to the lower end of the said burner tube; a coupling sleeve arranged on the enlarged 45 lower end of said burner tube into which said burner tip is threaded; and lugs on said burner tube adapted to engage said coupling whereby its rotation on said burner tube is 50 prevented.
5. In a gas lamp, the combination with a gas delivery pipe, of a chimney connected thereto, said chimney having an outwardly-projecting flange at its lower end; a downwardly-directed delivery nozzle; a valve for 55 controlling said delivery nozzle; a sleeve having openings in the sides thereof for the admission of air arranged about said nozzle; an inverted burner tube having a flange-like enlargement at its lower end, threaded through said chimney flange, arranged with its upper end projecting into said sleeve; an inverted burner tip having a threaded enlargement at its upper end corresponding in diameter to the lower end of the said burner tube; and a coupling sleeve arranged on the enlarged 60 lower end of said burner tube, into which said burner tip is threaded.
6. In a gas lamp, the combination with a gas delivery pipe, of a chimney connected thereto, said chimney having an outwardly-projecting flange at its lower end; a downwardly-directed delivery nozzle; a valve for 65 controlling said delivery nozzle; an inverted burner tube having a flange-like enlargement at its lower end, threaded through said chimney flange, arranged with its upper end ar- 70 ranged below said delivery nozzle; an inverted burner tip having a threaded enlargement at its upper end corresponding in diameter to the lower end of the said burner tube; a coupling sleeve arranged on the enlarged lower end of said burner tube into which said burner tip is threaded; and lugs on said burner tube adapted to engage said coupling whereby its rotation on said burner tube is 75 prevented.
7. In a gas lamp, the combination with a gas delivery pipe, of a chimney connected thereto, said chimney having an outwardly-projecting flange at its lower end; a downwardly-directed delivery nozzle; a valve for 80 controlling said delivery nozzle; an inverted burner tube having a flange-like enlargement at its lower end, threaded through said chimney flange, arranged with its upper end ar- 85 ranged below said delivery nozzle; an inverted burner tip having a threaded enlargement at its upper end corresponding in diameter to the lower end of the said burner tube; and a coupling sleeve arranged on the enlarged lower end of said burner tube, into which said burner tip is threaded.
8. In a gas lamp, the combination with a gas delivery pipe, of a chimney connected thereto, said chimney having an outwardly-projecting flange at its lower end; a downwardly-directed delivery nozzle; a valve for 90 controlling said delivery nozzle; a sleeve having openings in the sides thereof for the admission of air arranged about said nozzle; an inverted burner tube formed of non-heat-conducting material having a flange-like enlargement at its lower end, threaded through said chimney flange, arranged with its upper end projecting into said sleeve; an inverted burner tip formed of non-heat-conducting material having a threaded enlargement at its upper end corresponding in diameter to the lower end of the said burner tube; a coupling sleeve arranged on the enlarged 95 lower end of said burner tube into which said burner tip is threaded; and lugs on said burner tube adapted to engage said coupling whereby its rotation on said burner tube is 100 prevented.
9. In a gas lamp, the combination with a gas delivery pipe, of a chimney connected thereto, said chimney having an outwardly-projecting flange at its lower end; a downwardly-directed delivery nozzle; a valve for 105 controlling said delivery nozzle; a sleeve having openings in the sides thereof for the admission of air arranged about said nozzle; an inverted burner tube formed of non-heat-conducting material having a flange-like enlargement at its lower end, threaded through said chimney flange, arranged with its upper end projecting into said sleeve; an inverted burner tip formed of non-heat-conducting material having a threaded enlargement at its upper end corresponding in diameter to the lower end of the said burner tube; a coupling sleeve arranged on the enlarged 110 lower end of said burner tube into which said burner tip is threaded; and lugs on said burner tube adapted to engage said coupling whereby its rotation on said burner tube is 115 prevented.
10. In a gas lamp, the combination with a gas delivery pipe, of a chimney connected thereto, said chimney having an outwardly-projecting flange at its lower end; a downwardly-directed delivery nozzle; a valve for 120 controlling said delivery nozzle; a sleeve having openings in the sides thereof for the admission of air arranged about said nozzle; an inverted burner tube formed of non-heat-conducting material having a flange-like enlargement at its lower end, threaded through said chimney flange, arranged with its upper end projecting into said sleeve; an inverted burner tip formed of non-heat-conducting material having a threaded enlargement at its upper end corresponding in diameter to the lower end of the said burner tube; a coupling sleeve arranged on the enlarged 125 lower end of said burner tube into which said burner tip is threaded; and lugs on said burner tube adapted to engage said coupling whereby its rotation on said burner tube is 130 prevented.

- enlargement at its lower end, threaded through said chimney flange, arranged with its upper end projecting into said sleeve; an inverted burner tip formed of non-heat-conducting material having a threaded enlargement at its upper end corresponding in diameter to the lower end of the said burner tube; and a coupling sleeve arranged on the enlarged lower end of said burner tube, into which said burner tip is threaded.
9. In a gas lamp, the combination with a gas delivery pipe, of a chimney connected thereto, said chimney having an outwardly-projecting flange at its lower end; a downwardly-directed delivery nozzle; a valve for controlling said delivery nozzle; an inverted burner tube formed of non-heat-conducting material having a flange-like enlargement at its lower end/threaded through said chimney flange, arranged with its upper end below said delivery nozzle; an inverted burner tip formed of non-heat-conducting material having a threaded enlargement at its upper end corresponding in diameter to the lower 25 end of the said burner tube; a coupling sleeve arranged on the enlarged lower end of said burner tube, into which said burner tip is threaded; and lugs on said burner tube arranged to engage said coupling whereby its 30 rotation on said burner is prevented.
10. In a gas lamp, the combination with a gas delivery pipe, of a chimney connected thereto, said chimney having an outwardly-projecting flange at its lower end; a downwardly-directed delivery nozzle; a valve for controlling said delivery nozzle; an inverted burner tube formed of non-heat-conducting material having a flange-like enlargement at its lower end, threaded through said chimney flange, arranged with its upper end below said delivery nozzle; an inverted burner tip formed of non-heat-conducting material having a threaded enlargement at its upper end corresponding in diameter to the lower 35 end of the said burner tube; and a coupling sleeve arranged on the enlarged lower end of said burner tube, into which said burner tip is threaded; and lugs on said burner tube arranged to engage said coupling whereby its 40 rotation on said burner is prevented.
11. In a gas lamp, the combination with a gas delivery pipe, of a chimney connected thereto, said chimney having an outwardly-projecting flange at its lower end; a downwardly-directed delivery nozzle; a valve for controlling said delivery nozzle; an inverted burner tube formed of non-heat-conducting material having an upwardly-tapered threaded portion, threaded through said chimney flange, arranged with its upper end projecting into said sleeve; and an inverted burner tip on said tube.
12. In a gas lamp, the combination with a gas delivery pipe, of a chimney connected thereto, said chimney having an outwardly-projecting flange at its lower end; a downwardly-directed delivery nozzle; a valve for controlling said delivery nozzle; an inverted burner tube formed of non-heat-conducting material, having an upwardly-tapered threaded portion and a flange-like enlargement at its lower end, threaded through said chimney flange, arranged with its upper end below said nozzle; an inverted burner tip having a threaded enlargement at its upper end corresponding in diameter to the lower end of the said burner tube; and a coupling sleeve arranged on the enlarged end of said burner tube, into which said burner tip is threaded.

and lugs on said burner tube adapted to engage said coupling whereby its rotation on said burner is prevented.

13. In a gas lamp, the combination with a gas delivery pipe, of a chimney connected thereto, said chimney having an outwardly-projecting flange at its lower end; a nipple on said gas delivery pipe; a downwardly-directed delivery nozzle threaded upon the lower end of said nipple; a valve for controlling said delivery nozzle; a sleeve adjustably-arranged on said nipple having openings in the sides thereof for the admission of air and for the manipulation of said nozzle, said openings being of sufficient size to admit of the insertion or removal of said nozzle therethrough; an inverted burner tube formed of non-heat-conducting material having an upwardly-tapered threaded portion, threaded through said chimney flange, arranged with its upper end projecting into said sleeve; and an inverted burner tip on said tube.

14. In a gas lamp, the combination with a gas delivery pipe, of a chimney connected thereto, said chimney having an outwardly-projecting flange at its lower end; a downwardly-directed delivery nozzle; a valve for controlling said delivery nozzle; a sleeve having openings in the sides thereof for the admission of air arranged about said nozzle; an inverted burner tube formed of non-heat-conducting material having an upwardly-tapered portion threaded through said chimney flange, arranged with its upper end projecting into said sleeve; and an inverted burner tip on said tube.

15. In a gas lamp, the combination with a gas delivery pipe, of a chimney connected thereto, said chimney having an outwardly-projecting flange at its lower end; a nipple on said gas delivery pipe; a downwardly-directed delivery nozzle threaded upon the lower end of said nipple; a valve for controlling said delivery nozzle; a sleeve adjustably-arranged on said nipple having openings in its sides thereof for the admission of air and for the manipulation of said nozzle, said openings being of sufficient size to admit of

120
115
125
130

the insertion or removal of said nozzle therethrough; an inverted burner tube formed of non-heat-conducting material arranged with its upper end projecting into said sleeve; and

5 an inverted burner tip on said tube.

16. In a gas lamp, the combination with a gas delivery pipe, of a chimney connected thereto, said chimney having an outwardly-projecting flange at its lower end; a downwardly-directed delivery nozzle; a valve for controlling said delivery nozzle; a sleeve having openings in the sides thereof for the admission of air arranged about said nozzle; an inverted burner tube arranged through and detachably secured to said flange with its upper end projecting into said sleeve; and an inverted burner tip on said tube.

17. In a gas lamp, the combination with a gas delivery pipe, of a chimney connected thereto, said chimney having an outwardly-projecting flange at its lower end; a valve for controlling said delivery nozzle; an inverted burner tube formed of non-heat-conducting material arranged with its upper end arranged below said delivery nozzle; and an inverted burner tip on said tube.

18. In an inverted, incandescent gas burner, the combination with the gas delivery nozzle, of a burner comprising an inverted burner tube arranged with its upper end below said nozzle, said burner tube having a downwardly-tapered or contracted mixing chamber at its upper end delivering into a downwardly-expanding expansion chamber; an inverted burner tip detachably connected to said burner tube, the chamber of said tip being tapered or contracted downwardly, said burner tip having an internal annular shoulder at the upper end thereof; and a

40 screen seated on said shoulder, said mixing chamber, expansion chamber and burner tip chamber being of substantially the same length, as specified.

19. In an inverted, incandescent gas burner, the combination with the gas delivery nozzle, of a burner, comprising an inverted burner tube arranged with its upper end below said nozzle, said burner tube having a downwardly-tapered or contracted mixing chamber at its upper end delivering into a downwardly-expanding expansion chamber; an inverted burner tip detachably connected to said burner tube, the chamber of said burner tip being tapered or contracted downwardly, said burner tip having an internal shoulder at the upper end thereof; and a

55 screen seated on said shoulder, said mixing chamber, expansion chamber, and burner tip chamber being of substantially the same length, as specified.

20. In an inverted, incandescent gas burner, the combination with the gas delivery nozzle, of a burner, comprising an inverted burner tube arranged with its upper end below said nozzle, said burner tube having a

downwardly-tapered or contracted mixing chamber at its upper end delivering into a downwardly-expanding expansion chamber; an inverted burner tip detachably connected to said burner tube, the chamber of said burner tip being tapered or contracted downwardly, said mixing chamber, expansion chamber, and burner tip chamber being of substantially the same length, as specified.

21. In an inverted, incandescent gas burner, the combination with the gas delivery nozzle, of a burner, comprising an inverted burner tube arranged with its upper end below said nozzle, said burner tube having a downwardly-tapered or contracted mixing chamber at its upper end delivering into a downwardly-expanding expansion chamber, the walls of said mixing chamber having a parabolic curvature; an inverted burner tip detachably connected to said burner tube, the chamber of said burner tip being tapered or contracted downwardly, said mixing chamber, expansion chamber and burner tip chamber being of substantially the same length, as specified.

22. In an inverted incandescent gas burner, the combination with a gas delivery nozzle, of a burner comprising an inverted burner tube arranged with its upper end below said nozzle, said burner tube having a downwardly tapered or contracted mixing chamber at its upper end delivering into a downwardly expanding expansion chamber; an inverted burner tip, the chamber of said burner tip being tapered or contracted downwardly, said burner tip having an internal annular shoulder at the upper end thereof; a conical screen seated on said shoulder and projecting upwardly into said expansion chamber; and a conical deflector carried by

100 said screen, said deflector being interposed between the said delivery nozzle and the mouth of the burner tip, and projecting upwardly from said screen into the lower end of the mixing chamber, as specified.

23. In an inverted incandescent gas burner, the combination with a gas delivery nozzle, of a burner comprising an inverted burner tube arranged with its upper end below said nozzle, said burner tube having a downwardly tapered or contracted mixing chamber at its upper end delivering into a downwardly expanding expansion chamber; an inverted burner tip, the chamber of said burner tip being tapered or contracted downwardly; a conical burner screen arranged at the upper end of said burner tip and projecting upwardly into said expansion chamber; and a conical deflector carried by

115 said screen, said deflector being interposed between the said delivery nozzle and the mouth of the burner tip, and projecting upwardly from said screen into the lower end of the mixing chamber, as specified.

24. In an inverted, incandescent lamp, the
